[57] CLAIM

The ornamental design for a combined storage and exercise therapy apparatus, as shown and described.

DESCRIPTION

FIG. 1 is a perspective view of a first embodiment of a combined storage and exercise therapy apparatus showing my new design;

FIG. 2 is a front elevational view of said first embodiment, said front elevational view being identical to rear, left side and right side elevational views thereof;

FIG. 3 is a top plan view of said first embodiment;

FIG. 4 is a bottom plan view of said first embodiment;

FIG. 5 is a perspective view of a second embodiment of a combined storage and exercise therapy apparatus showing an alternative of my new design;

FIG. 6 is a front elevational view of said second embodiment, said front elevational view being identical to rear, left side and right side elevational views thereof;

FIG. 7 is a top plan view of said second embodiment; and,

FIG. 8 is a bottom plan view of said second embodiment.
